ATTORNEYS

UNITED STATES PATENT OFFICE.

CHARLES GARRISON, OF BROOKLINE, MASSACHUSETTS.

LIFE-PRESERVER.

1,271,154.

Specification of Letters Patent.

Patented July 2, 1918.

Application filed November 17, 1916. Serial No. 131,869.

To all whom it may concern:

Be it known that I, CHARLES GARRISON, a citizen of the United States, residing at Brookline, in the county of Norfolk and 5 State of Massachusetts, have invented new and useful Improvements in Life-Preservers, of which the following is a specification.

The present invention comprises an improved life preserver having novel features 10 which serve useful purposes in an improved manner. Such novel features and the objects served thereby are fully set forth in connection with a detailed description of one embodiment of my invention, in the following specification with reference to the 15 drawings which form a part of the application. In the drawings,

Figure 1 is a front elevation of my novel life preserver in the position which it occupies on the person of the wearer.

Fig. 2 is a rear elevation on a smaller scale of the life preserver.

Fig. 3 is a side view showing the position assumed when the person wearing it is in 25 the water.

Figs. 4 and 5 are vertical central sections taken through the front and rear portions of the life preserver on the lines 4, 4 of Fig. 1 and 5, 5 of Fig. 2, respectively.

30 Fig. 6 is a cross section of the front portion of the article taken on line 6—6 of Fig. 1.

Fig. 7 is a plan view of a case or cover adapted to receive the preserver.

35 Fig. 8 is a cross section of the case and of the contained life preserver taken on line 8—8 of Fig. 7.

Fig. 9 is a side view illustrating the use 40 of the preserver in its case as a cushion.

Fig. 10 is a perspective view showing the manner in which the preserver with its case 45 may be folded and retained in folded position for transport.

The same reference characters indicate 50 the same parts in all the figures.

The life preserver may in accordance with this invention comprise a front portion or element 11, a rear portion 12, shoulder straps 13, 13 and arm pit straps 15, 15. In use the 55 head of the wearer is inserted through the opening between the shoulder straps and the arms and the shoulders are inserted through the openings between the straps 13 and 15,

the latter straps then lying close to the body of the user and passing beneath his arms. 55

Without intending to restrict my invention as to the materials from which the life preserver may be made, I will say that I prefer to make it of an outer skin or fabric, the pieces of which are properly cut and secured together by stitching or otherwise, and a stuffing or filling of buoyant material. A desirable material for the stuffing is Java kapok, otherwise commonly known as silk floss, which is a light, fluffy vegetable fiber 60 very buoyant, resilient, and repellent to water. I may, however, use any of the other materials and substances, such for example as cork, in slabs or granular condition, which are known, or may hereafter be discovered, to be suitable for the filling of life preservers. 70

At the lower end of the front section or element of the preserver is a section 16 which is in effect hinged to the section 11 75 so that it may turn or bend up forwardly with respect thereto as shown in Fig. 3. A convenient way to provide this hinge is to separate the stuffing or filling of the sections 11 and 16 enough so that the skin or walls 80 at the front and back of this portion of the life preserver may be brought close together, and then to secure these breadths or sheets of the covering skin in this position by a line of stitches 17 or by other means. I use the 85 term "hinge" in this specification to designate the line on which the section 16 may turn or bend relatively to the portion 11, however such a bending line may be formed. 90

This hinge or hinge line definitely locates the position at which the part 16 swings relatively to the part 11, and is a very important feature of the invention, for reasons as follows. The sections 11 and 12 are constructed to have substantially equal 95 buoyancy, that is, they have approximately equal dimensions and quantity or bulk of filling. The portion 16, however, constitutes a buoyant element at the front of the life preserver for which there is no counterpart at the back and, being at the lower edge of the front portion it is well submerged when the person wearing the life preserver is in the water, therefore exerting a strong lifting effect. This additional 100 buoyant effect being applied to the forward 105

part of the life preserver tends to throw the shoulders and head of the wearer backward, thereby keeping the wearer's face well above the water in case he should become unconscious and unable to exert himself voluntarily to that end. The hinge connection of the part 16, which may be called the reserve buoyant element, enables the latter to swing into a substantially horizontal position under the upward pressure of the water, whereby it still further tends to throw the upper part of the wearer's body backward. But it does not interfere with swimming, because when the wearer swims it will swing back to the position in continuation of the section 11 and cause no additional impedance to the progress of the body through the water.

Another important feature of the invention resides in the arm pit straps 15, which are an integral part of the life preserver and are stuffed with the buoyant material so that they have considerable breadth and thickness. Each of these straps is an integral unit permanently connected at its opposite ends to the main parts of the preserver. They do not at all offer any hindrance to the putting on of the life preserver, but when the latter is once on, they serve the purpose of holding the sections of the preserver close to the body of the wearer, and of locking the preserver in place by extending under the wearer's arms, and also of applying the lifting effect of the life preserver to the user under his arms, where it should be applied; but in doing so they do not tend to stop circulation of the blood, because the soft stuffing with which they are filled distributes the applied force uniformly over a wide area.

I provide tapes 18 which are secured to the bottom of the rear section and may be passed around the body and tied in front, but these tapes are provided merely to add to the comfort of the wearer, and are entirely unnecessary so far as the vital function of securing the preserver to the body is concerned. This function is effectively performed by the straps 15.

It will be seen from the foregoing that the life preserver may be put on by being slipped over the head and arms, and that upon being so put on it is efficiently secured, there being no strap, buckles, or other fastenings to be secured in order to retain it in place. This is a novel feature so far as I am aware and is an important element of safety, as thereby all danger of improperly secured fastenings becoming detached is avoided, and the time required to secure the preserver to the person is reduced. Many situations are conceivable in which every instant of time saved in applying a life preserver is of the

utmost importance; and it is equally important to insure that the securing means will not become released when the wearer is exhausted or unconscious and thus incapable of helping himself.

I provide a case to contain the life preserver, such case being essentially a bag 19 having an opening at one end, as shown in Fig. 7, into which the life preserver may be inserted. A fastener 20 is provided to hold the lips of the end opening together. The flexibility between the front and rear sections, caused by the small amount of material at the region of the connecting straps 13 and 15, enables the cover with the contained preserver to be easily bent, wherefore it may serve as a seat and back cushion for a boat, as shown in Fig. 9, where 21 represents a fragment of a canoe, or a chair, etc. The cover 19 is provided with handle straps 22 and 23 at opposite ends, whereby the cushion constituted as above described may be used as a life preserver in case of sudden upsetting of the boat, when there is not time enough to remove the preserver from its case and put it on. The cushion may also be folded double, as shown in Fig. 10, and secured in that position by flaps 24 having fasteners 25 which co-act with fasteners 26 at the opposite end of the cushion, the handle straps 22 and 23 being then brought together where they may be grasped in the manner of a hand bag, enabling the life preserver to be very easily carried by travelers embarking on a sea voyage.

What I claim and desire to secure by Letters Patent is:

1. A life preserver comprising front and back sections stuffed with light buoyant material, and permanently connected shoulder and arm pit straps connecting said sections and arranged with openings between them for the head and arms of the wearer, the arm pit straps giving support under the arms to the wearer when in the water, and by reason of their permanent connection with the sections being incapable of becoming unfastened, and the front section extending downwardly beyond the arm pit straps and being separated from the rear section, whereby when otherwise unconfined, it is effective to keep the face of the wearer from falling forward into the water.

2. A life preserver constructed of skins or coverings of flexible fabric and a stuffing of light buoyant material, said preserver being formed with front and rear sections and connecting straps, two of said straps being arranged to pass over the shoulders on opposite sides and close to the neck of the wearer, and two other straps arranged to pass under the arm pits to afford support to the wearer at those points when in the water, said straps

being so permanently connected with the front and rear sections as to be incapable of becoming accidentally disconnected, and the front and rear sections being otherwise separate and unconnected with one another and having portions which extend below the arm pit straps, the flexible construction of such

sections enabling them to bend, whereby when otherwise unconfined, the depending part of either section is adapted to be raised 10 by its buoyancy when in the water.

In testimony whereof I have affixed my signature.

CHARLES GARRISON.
